UNITED STATES PATENT OFFICE.

PERCY SMITH, OF DETROIT, MICHIGAN.

CHECK-HOLDER FOR RAILWAY-CARS.

1,331,682.

Specification of Letters Patent.

Patented Feb. 24, 1920.

Application filed March 25, 1918. Serial No. 224,666.

To all whom it may concern:

Be it known that I, PERCY SMITH, a citizen of the Dominion of Canada, residing at Detroit, in the county of Wayne, State of Michigan, have invented certain new and useful Improvements in Check-Holders for Railway-Cars; and I do hereby declare the following to be a full, clear, and exact description of the invention, such as will enable others skilled in the art to which it app pertains to make and use the same.

The invention relates to a check holder, and more particularly to the class of ticket or check holders for use in railway cars.

The primary object of the invention is the provision of a check holder of this character, wherein the same is made from two parts, preferably sheet metal and is readily and easily assembled for use in supporting checks or tickets, the construction of the holder being novel in form to positively retain the tickets or checks placed therein and to assure easy accessibility for the removal of the tickets or checks therefrom.

Another object of the invention is the provision of a check holder of this character, which is extremely simple in construction possessing minimum parts, thoroughly reliable and efficient in its purpose, and economical and inexpensive to manufacture.

With these and other objects in view, the invention consists in the features of construction, combination and arrangement of parts as will be hereinafter fully described, illustrated in the accompanying drawing and pointed out in the claim hereunto appended.

In the accompanying drawing:—

Figure 1 is a perspective view of the holder constructed in accordance with the invention.

Fig. 2 is a plan view of the blank from which the body of the holder is made.

Fig. 3 is a perspective view of the back or base of the holder.

Fig. 4 is a perspective view of the body separated from the back or base and in its completed form.

Similar reference characters indicate corresponding parts throughout the several views in the drawing.

Having more particular reference to the drawing, the check holder comprises a body A and a back or base B both being herein after fully described.

The body A is preferably made from a flat

blank of sheet metal cut to form the upper and lower intermediate portions 5 and 6 respectively which constitute the front walls of the individual pockets 7 formed by the body A, the blank being further cut to provide the side walls 8 for said pockets 7 which are superposed with relation to each other. The side walls 8 of the body A are formed with the outwardly curved edges 9 and the sections 5 and 6 are united for a distance of their length with the sides 8 which are foldable on the crease lines 10 indicated in the blank shown in Fig. 2 of the drawing, while the remaining portions of the sections 5 and 6 are curved correspondingly to the curved edges 9 so that the pockets 7 taper downwardly from the upper open ends thereof and these sections 5 and 6 are held in their curved formation in a manner presently described.

The back or base B of the holder comprises an elongated flat plate 11 formed with reduced end ears 12 which are suitably perforated for receiving fasteners to attach the back or base of the holder upon a chair in a railway car or on the side wall of said car. The sides 8 of the body A are formed at the straight free edges thereof with bendable tongues 13 which engage in suitable slots 14 formed in the plate 11 and are turned over against the rearmost face of the plate for the secure fastening of the body, A thereon.

Cut and bent outwardly from the plate 11 transversely thereof are lips or flanges 15 in which are engaged the lower ends 16 of the sections 5 and 6 constituting the front of the body A and in this manner the bottoms of the pockets 7 are closed.

Cut and stamped outwardly from the plate 11 longitudinally thereof are outwardly bowed leaf springs 17 which play against the sections 5 and 6 interiorly of the pockets 7 for frictionally holding tickets or checks when placed within the pockets, yet the said checks or tickets can be readily withdrawn through the open ends of the pockets when it is required to move the checks from the holder.

The upper edges of the sections 5 and 6 constituting the fronts of the pockets are formed with medial notches 18 to enable a finger grip upon the tickets or checks when within the pockets.

From the foregoing it is thought that the construction and manner of use of the holder

will be clearly understood and therefore a more extended explanation has been omitted.

What is claimed is:—

As an article of manufacture a device for 5 yieldably holding checks consisting of a spring metal plate having longitudinally spaced tongues struck therefrom and connected therewith at their upper ends and a transverse lip below each tongue and a second plate comprising longitudinal side members in parallel spaced relation and longitudinally spaced central members connected

with the side members at their upper ends and lying against the edges of the side members and having their lower end portions engaged behind the lips of the first plate and to which first plate the longitudinal side members are connected.

15

In testimony whereof, I affix my signature, in the presence of two witnesses.

PERCY SMITH.
